[57] CLAIM

The ornamental design for a wire shelf, substantially as shown.

DESCRIPTION

FIG. 1 is a top plan view of a wire shelf showing my new design;

FIG. 2 is a front elevational view thereof;

FIG. 3 is a left side elevational view thereof, the right side elevational view being a mirror image thereof;

FIG. 4 is a rear elevational view thereof; and

FIG. 5 is a bottom plan view thereof.

FIG. 6 is a perspective view thereof.

Fig. 1.

Fig. 6.
